UNITED STATES PATENT OFFICE.

SOLOMON C. HOLLISTER, OF SWARTHMORE, PENNSYLVANIA, ASSIGNOR TO JOHN H. MCCLATCHY, OF PHILADELPHIA, PENNSYLVANIA.

FORM WORK FOR CASTING WALLS AND THE LIKE.

Application filed April 8, 1926. Serial No. 100,627.

For many years, walls and structures of concrete have been cast in molds of one kind and another; but although numerous efforts have been made, it has heretofore been found 5 impracticable to produce such a wall with a continuous surface true and plane enough to dispense with the need for a coat of plaster, where a smooth appearance is important. The present invention relates to molds or 10 forms for casting walls and the like of plastic material and has for its principal objects to insure the production of a wall with a continuous plane surface suitable for use in homes and other buildings where a 15 neat appearance is important; also to dispense with the need for a coat or coats of plaster and thereby save the cost thereof; also to obtain other advantages hereinafter appearing.

20 The invention consists principally in form units in the form of flat plates adapted to be assembled edgewise and with their adjacent margins provided with means for insuring proper alinement of the units with 25 the faces of adjacent plates flush. It also consists in the parts and arrangements of parts hereinafter described and claimed.

In the accompanying drawing wherein like symbols refer to like parts wherever 30 they occur,

Fig. 1 is a perspective view of part of a form work embodying my invention;

Fig. 2 is a horizontal cross-section through the form work of Fig. 1;

35 Fig. 3 is a similar cross-section illustrating a modification of the form work;

Fig. 4 is an enlarged sectional detail view through a guiding strip and adjacent portions of stiffening members; and

40 Fig. 5 is an enlarged fragmental view of the corner portions of two units approaching contact in the course of assembly.

45 My form work comprises a number of units adapted to be secured together edge to edge in flush alinement. Each unit comprises a flat plate 1 of fairly stiff metal, such, for instance, as a No. 10 gage steel plate. Along one of its margins is secured a suitable stiffening member, such, for instance, as a channel iron 4 which is riveted thereto by rivets whose heads are countersunk flush with the surface of the plate, the rivets passing through one flange of the channel, and the edge of the plate being dis-

posed beyond the channel and extending 55 parallel therewith. On the opposite flange of the channel is mounted flatwise a strip 5 whose margin projects beyond the channel. The portion of said projecting margin adjacent to the channel is substantially parallel 60 with the projecting margin of the plate, while the outer portion of said strip is bent slightly or beveled on its inner surface, as shown at 14, to widen the distance between said outer portion of the strip and 65 the edge of said plate. This arrangement forms a guide-way for bringing cooperating units into proper register, as herein-after described.

The opposite margin of said plate 1 is 70 also provided with a stiffening member, such as a channel iron 2 that is secured thereto by rivets extending through one flange of the channel iron and countersunk flush with the surface of the plate, the web of this 75 channel iron being disposed beyond the edge of the plate and extending parallel therewith. Preferably the two channel irons are of the same depth, so that when two similar or counterpart units are assembled, the 80 channel of one unit is readily and easily entered between the guide strip 5 and projecting margin of the plate of the other suit. In use, suitable clamps 12 are applied to adjacent channels and the adjacent edges of 85 the plates are thereby pulled tight together. To permit this, the margin of one plate should project far enough beyond the adjacent channel of its unit to overlap the un-covered portion of the channel of the next 90 unit and reach the edge of its plate.

In practice it is preferable to make the units identical so that they will be interchangeable. If desired, however, the units 95 may be made in sets, both of the stiffening channels of one set extending beyond the edge of the form-plate, and both stiffening channels of the other set being wholly within the edges of their form-plate.

The units above described are used after 100 the manner of ordinary form-work. In assembling them, the strengthening channel that projects beyond the form-plate of one unit is entered between the projecting portion of the form-plate of the adjacent unit and the guide strip thereof, whereby said units are brought into proper registry with 105 each other with the surfaces of their form-

plates flush. For this operation suitable clamps 12 are applied to the channels to draw them tight together. Straight rigid walers 10 are suitably positioned and against these the units are lined up and secured in any suitable manner, as by ordinary ties 7 that pass through holes 8 in the form-plates and are provided with holes for wedge keys 9 or with locking pins 15. Where wide form-plates are used, it is preferable to stiffen them with channel irons 16 or the like extending through the middle portion thereof; and in such case, spacing blocks 11 are used on the back thereof of the same thickness with the guide plates 5, for cooperation with the walers in obtaining the correct alinement of the middle portions of the face plates.

The manner of assembling and interlocking the units brings them into correct registration with a true plane surface and assures the maintenance of such surface during the casting operation. As each of the opposite margins of the stiff plate are greatly stiffened by the channel irons, there is no danger of the margins of said units flexing, puckering or distorting in any manner. It is particularly noted that the marginal portion of the form-plate projecting beyond its channel iron is not only narrow but, in use, is thoroughly supported throughout its length by the channel iron of the adjacent unit that constitutes a seat therefor. Thus, edge contact of adjacent plates and flush surface alinement thereof are both obtained.

In practice, straight horizontal walers, preferably in the form of rigid channels or I-beams are used to insure proper alinement of the units, and the stiffening members of the units have a wide flat bearing against them. It is noted, in this connection, that the counter-sinking of the rivets that hold the guide plates on the channel irons permits such a flat bearing of such channels against the walers. By this arrangement, the units are lined up against the walers, and the guiding joints between units automatically bring the faces of the form-plates of the units into flush register.

In the construction hereinbefore described, the guide function, whereby the flush registration of the mold plates is obtained, resides in a guide plate mounted on the back of the stiffening channel iron. In the modification illustrated in Fig. 3, the guiding function is accomplished in a different manner. According to this modification, spacing strips 19, 20 intervene between the form-plate and the respective channels along the margins thereof. These spacing strips are of even thickness. In the case, however, of the strip 19 that is associated with the margin of the plate that terminates short of the web of the stiffening channel iron, its thickness decreases gradually

towards its outer margin from a line far enough from the edge of the form-plate to leave sufficient bearing for the form-plate of the next adjacent unit. The inclined portion of the spacing strip thus functions as a guide-way that facilitates the assembling of the units and the proper guiding of the form-plate into flush register with the next form-plate while the flat projecting portion of such spacing strip affords ample support for the projecting margin of the adjacent form-plate in its final position.

The foregoing description sets forth the manner of assembling the units in horizontal alinement, in which case the stiffening channels are applied to the vertical margins of the sheets. Obviously the same idea is applicable to the assembling of the units in vertical alinement. For this purpose, the units may be arranged with the marginal stiffening and assembling devices disposed horizontally; or they may be provided with such devices along their horizontal margins as well as along their vertical margins. This latter arrangement is illustrated in the upper portion of Fig. 1 of the drawing.

What I claim is:

1. A form unit for casting plastic material comprising a plate and stiffening members on opposite margins of said plate arranged with their outer edges spaced side-wise from the outer edges of said plate suitably for cooperation with counterpart plates, said unit having an inclined surface adapted to guide such counterpart unit into register therewith.

2. A form unit for casting plastic material comprising a plate and channel-shaped stiffening members on opposite margins of said plate with their flanged portions extending inwardly, one of said members extending beyond the adjacent edge of said plate, and the opposite edge of said plate extending beyond the outer edge of the adjacent stiffening member, said last mentioned stiffening member having a guide piece on its outer flange extending beyond the web thereof and having an inclined surface constituting a guide for a similar stiffening member on an adjacent plate.

3. A form unit for casting plastic material comprising a plate and stiffening members on opposite margins of said plate, one of said members extending beyond the adjacent edge of said plate, and the opposite edge of said plate extending beyond the outer edge of the adjacent stiffening member, said unit having an inclined surface arranged for cooperation with a counterpart unit to bring their plates into edge contact and flush alinement with the projecting margin of the plate of one unit overlapping the uncovered portion of the stiffening member of the other unit.

4. A formwork for casting walls of plastic

- material comprising a plurality of units consisting of plates having angular stiffening members secured along opposite margins in such positions that the edges of adjacent 5 plates meet over one of such stiffening members, one of said stiffening members having a strip secured thereto that has an inclined surface arranged to guide the units into correct position.
- 10 5. A formwork for casting walls of plastic material comprising a plurality of units consisting of plates having angular stiffening members secured along opposite margins in such positions that the edges of ad- 15 jacent plates meet over one of such stiffening members, one of said stiffening members having a strip secured thereto substantially parallel with the plate on which said stiffening member is mounted but which projects beyond said stiffening member and 20 has the outer portion of its inner surface inclined to form a guide for the adjacent stiffening member.
6. A formwork for casting walls of plastic 25 material comprising a plurality of units consisting of plates having channel-like stiffening members secured along their margins, some of said channel-like members being positioned to extend beyond the edges of 30 their plates and some of them being positioned wholly within the edges of their plates to afford support for the projecting margins of adjacent plates, some of said channel-like members being provided with guide pieces 35 with inclined surfaces against which the ad-

jacent stiffening member rides to correctly position adjacent units.

7. A formwork for casting flat walls of plastic material comprising a plurality of units consisting of flat plates having stiffening members on opposite margins and in their middle portions, said marginal members being arranged to permit said plates to abut edgewise over the same stiffening members, and straight rigid walers against which said units abut. 40

8. A form work for casting walls of plastic material comprising a plurality of units consisting of plates having channel shaped stiffening members secured along their margins with their flanges extending inwardly, some of said stiffening members being positioned to extend beyond the edges of their plates and some being positioned wholly within the edges of their plates to afford support for the projecting margins of adjacent plates, those stiffening members that are wholly within the margins of their plates having guide pieces secured flatwise against their outer flanges and extending beyond the webs thereof and having their projecting portions formed with inclined surfaces against which the adjacent stiffening member rides to correct position and straight rigid walers against which the guide plates 55 60 65 abut. 65

Signed at Philadelphia, Pa., this 7th day of April, 1926.

Certificate of Correction.

Patent No. 1,640,997.

Granted August 30, 1927, to

SOLOMON C. HOLLISTER.

It is hereby certified that error appears in the printed specification of the above-numbered patent requiring correction as follows: Page 1, line 83, for the word "suit" read *unit*; and that the said Letters Patent should be read with this correction therein that the same may conform to the record of the case in the Patent Office. Signed and sealed this 4th day of October, A. D. 1927.
